[57] CLAIM

The ornamental design for a car battery plug, as shown and described.

DESCRIPTION

FIG. 1 is a front view showing our new design;

FIG. 2 is a left side view thereof;

FIG. 3 is a right side view thereof;

FIG. 4 is a rear view thereof;

FIG. 5 is a top view thereof;

FIG. 6 is a bottom view thereof; and,

FIG. 7 is a cross-sectional view thereof taken along line 7—7 of FIG. 1.

FIG. 1

FIG. 4

FIG. 2

FIG. 3

FIG. 5

FIG. 6

FIG. 7
